UNITED STATES PATENT OFFICE

ELIHU D. WATT, OF LA GRANGE, ILLINOIS, ASSIGNOR TO RAYMOND CONCRETE PILE COMPANY, OF NEW YORK, N. Y., A CORPORATION OF NEW JERSEY

SECTIONAL FILE

Application filed July 14, 1928. Serial No. 292,838.

This invention relates to piles, especially so-called sectional or "composite" piles, and its chief object is to provide a secure bonding of the sections end to end in such manner as 5 to effectually resist stresses tending to separate the sections, as is apt to result from the heaving of the soil pushing upwardly on the upper section or sections. Another object is to provide bonding means which will completely seal the joint against entry of mud 10 and water. Another object is to provide effective means for equalizing the diameter of the upper ends of wood piles so that wood piles of different diameters can be used with standard size superimposed sections and permit driving shells for casting the latter sections without subjecting the shells to excessive lateral pressures tending to distort the same or smooth out their corrugations. A 15 further object is to provide bonding means which shall also serve to protect the head of the wood section to prevent brooming and splintering in driving. Another object is to provide bonding means which serves, in effect, 20 to provide a tenon on the upper end of the wood pile for envelopment by the concrete of the cast-in-place upper section. A further object is to provide bonding means which also provides a recess or socket at the top of 25 the pile into which the concrete upper section extends. To these and other ends the invention comprises the novel features and combinations hereinafter described.

In carrying out my invention in the preferred manner as applied to a composite pile having a lower wood section, I arrange around the upper end of the wood section, before or after driving, a short sleeve of sheet metal, usually steel, of such internal diameter 35 as to leave an annular space of suitable radial width between the sleeve and the pile. The annular space is then filled with concrete or equivalent material, preferably of such consistency as to flow readily so that it will come 40 into actual contact with every part of the inner surface of the sleeve and the encircled portion of the pile. The sleeve is corrugated circumferentially, the corrugations being preferably in the form of screw threads. 45 When the concrete has set and hardened I

then have on the upper end of the pile a threaded steel collar backed and reinforced with concrete, to which a similarly corrugated shell for the upper section can be screwed.

55

Referring now to the accompanying drawings,

Fig. 1 is a plan view of the upper or head end of a wood pile laid on its side, with the corrugated sheet steel band or sleeve (shown 60 in section) arranged thereon.

Fig. 2 is a similar view, partly in section, of the pile after filling the sleeve with concrete.

Fig. 3 is a side view of a wood pile such as 65 is shown in Figs. 1 and 2, driven into the ground, with the corrugated shell for the upper concrete section screwed on to the coupling collar.

Fig. 4 is a side view showing the bonding 70 collar (in section) applied to a wood pile having a tenon at its upper end.

Fig. 5 is a side view showing a convenient tool, and its use, for in effect lining up a wood pile which has got out of plumb in driving, 75 so that the shell for the upper section can be arranged in vertical position thereon.

Fig. 6 is a sectional view of a form of the invention in which the collar extends above the top of the pile to form a socket for the 80 upper section.

Fig. 7 is a sectional view showing the invention used with two wood sections.

Fig. 8 is a side view showing a modification, in which the corrugations of the collar 85 and shell are plain, or non-helical.

Fig. 9 is a sectional view showing another modification, in which the concrete collar is reinforced internally, the external reinforcing sleeve being omitted.

Fig. 10 is a side view, partly in section, of another modification, in which the collar is uncorrugated.

Referring particularly to Figs. 1, 2 and 3, a wood pile for the lower section of a composite pile is shown at 10. It is usually desirable to shape the head end roughly with an axe or adze, and provide the same with notches, as 11, for better grip by the concrete. The corrugated sleeve or band 12 is 95 100

arranged at a suitable distance from the end and held temporarily in position (by any suitable means, not shown) to make the annular space 13 between the sleeve and the 5 pile substantially uniform in radial width. If, as is usual, the pile has not been driven and is lying on its side, both ends of the sleeve are closed by any convenient means, as for example by wrapping canvas or sack- 10 ing, not shown, around the ends of the sleeve. The concrete is then poured in through the opening 14. The sleeve is thus solidly backed with concrete, which is in turn backed by the wood pile, so that the sleeve is practically 15 incapable of distortion or deformation by stresses and pressures encountered in subsequent driving, and at the same time the sleeve reinforces the concrete backing against cracking or shattering.

20 The wood section is driven to the desired depth, leaving the coupling collar at a suitable position above the ground, as in Fig. 3 for example, and the corrugated shell 15 for the upper section is screwed down on the 25 collar. This shell may be in one piece, or in two or more sections screwed one into the other, the shell shown being composed of two such sections. It will be observed that the collar provides a shoulder 16 at its top, thus 30 making a tenon 17 of the protruding end of the wood pile. If desired the lower portion of the steel sleeve may have a slight flare (not shown) to give a tighter fit with the shell, but ordinarily it is not necessary 35 since the shell and the sleeve can easily be made with a close enough fit, or, if not, the sleeve may be coated with any suitable composition to make the joint sufficiently watertight if the pile is to be sunk in very wet soil.

40 The assembly shown in Fig. 3 is now driven, using a suitable core in the shell, as is customary. As the driving proceeds the collar plows a hole for the shell above, so that the latter is not compelled to displace the 45 soil and has to withstand only the driving friction resulting from inward movement of the soil after the collar has passed. Hence the liability of distortion of the shell is greatly decreased, to such an extent that in 50 some cases a smooth or uncorrugated core may be used. By enlarging the lower portion of the collar the effect described can be further increased, as will be readily understood.

55 When the shell is sunk to the desired depth it is filled with concrete in the usual way, forming the upper section of the composite pile. The upper section thus surrounds the upper end or "tenon" of the wood pile and 60 bears on the top of the latter and also on the shoulder 16. If under special conditions greater strength at the joint is desired the wood pile may be provided with a tenon of the usual kind, as in Fig. 4, for example, 65 which shows a tenon 18 formed by turning

down the head of the pile in the customary way. In some cases, due usually to ground conditions, the wood pile may get out of plumb in driving, as is shown for example, with perhaps some exaggeration, in Fig. 5. 70 The shell for the upper section can, however, easily be set or aligned up in a truly vertical position on the wood pile for driving. For this purpose a corrugated steel sleeve 19 is screwed down on the collar 12, leaving its end well above the collar, and into the sleeve is inserted a tool having a head 20, which may be corrugated and which is hollow to accommodate the protruding end or tenon of the pile and is carried by arms 21 depending from a handle or actuating member 22. The tool is pushed laterally, thereby straightening up the sleeve, as indicated, such effect being accompanied by compression or crimping of the screw-thread corrugations on one side of the coupling sleeve 19 and expansion of the same on the other. The tool can now be removed and the shell for the upper section fitted to the sleeve.

In the construction shown in Fig. 6 the corrugated reinforcing sleeve, as shown at 22a, is partially embedded in the concrete collar 23, which itself extends above the top of the wood pile to form a socket and is provided with additional reinforcement, as rods 24 and rings 25. The shell 15 for the upper section is screwed to the protruding end of the sleeve. In driving the shell the core (not shown) fits down into the concrete collar so as to drive on top of the wood pile. When the upper section is cast the concrete fills the socket in the collar, forming a tenon, and may, of course, have suitable reinforcing members, not shown, extending into the socket to give increased beam strength at the joint. This form of the invention is especially advantageous where conditions of extreme upheaval are encountered, since the concrete collar, being larger in diameter than the sleeve 22, makes a hole with correspondingly larger clearance around the upper shell. The embedded portion of the sleeve 22 may have suitable holes or openings, not shown, to bond the concrete on the inside and outside together, if desired.

The invention may also be used for connecting two wood sections together, as in Fig. 7 for example, in which the abutting ends of the sections, designated 26, 27, are provided with collars and the bond is formed by a connecting sleeve 28.

Helical, or screw-thread, corrugations are preferred but they may be non-helical, in which case the corrugated upper shell may 125 be split at its lower end to admit the collar on the lower section, after which the split portion can be bound with wire to hold it firmly on the collar. This construction is illustrated in Fig. 8, in which the shell 29 130

is split at 30 and is tied on the collar, on the wood pile 10, by wires 31.

In some cases I may dispense with the sheet metal sleeve and provide the collar with internal reinforcement, as in Fig. 9 for example. In this figure the collar, designated by 32, is cast on the wood pile 10 in a suitable form or mold, preferably corrugated, and is provided with longitudinal reinforcing bars 33 and reinforcing rings 34.

If the collar is not corrugated I prefer to give it a downward taper in order to afford more secure connection with the shell above. Thus in Fig. 10 the collar 36, which may have its reinforcement on the outside in the form of a sheet metal sleeve, or inside as in Fig. 6, is tapered downwardly and the lower end of the shell 37 is tapered to fit, with its edge bent under the collar. In this case the wood pile, shown at 10, is "shelled up" before it is driven, the shell being drawn up over it. The shell, or at least the upper portion of it, may be corrugated if desired.

It is to be understood that the invention is not limited to the specific constructions herein described but may be carried out in other ways without departure from its spirit.

I claim—

1. A composite pile comprising a wood pile provided at its head end with a collar comprising a metal sleeve and a backing of concrete between the sleeve and the pile to reinforce the same against lateral pressures, a sheet metal pile shell locked to the collar on the wood pile, and a filling of concrete in the shell.

2. A composite pile comprising a lower section of wood having at its upper end a collar comprising a sheet metal sleeve formed with screw-threaded corrugations, and a filling of concrete cast between the sleeve and wood section, the concrete engaging the section to prevent longitudinal displacement of the collar; and an upper section comprising a sheet metal pile shell screw-threaded on said collar, and a filling of concrete in the shell.

3. A composite pile comprising a lower wood section having at its upper end a cast-on reinforced concrete collar provided with external screw-thread corrugations, a connecting sleeve having like corrugations screwed to the collar, a pile shell for the upper section having like corrugations screwed to the connecting sleeve, and a filling of concrete in the shell and bearing on the lower wood section.

4. A composite pile comprising a lower section of wood having at its upper end and below the top, a collar comprising a helically corrugated sheet metal sleeve and a cast-in-place filling of concrete between the sleeve and the wood, a helically corrugated sheet metal connecting sleeve screwed to the collar, a helically corrugated pile shell for the upper section screwed to the connecting sleeve, and

a filling of concrete cast in the shell and embedding at its lower end the upper end of the lower wood section above the collar thereon.

5. Method of making composite piles, comprising casting at the upper end of a lower wood section a reinforced concrete collar having external circumferential corrugations, coupling to the collar an upper pile shell of sheet metal formed with circumferential corrugations, and filling the shell with concrete.

6. Method of making composite piles, comprising casting on a lower wood section a collar of reinforced concrete having external helical corrugations, screwing on the collar a connecting sleeve of helically corrugated sheet metal, screwing on the sleeve an upper pile shell of sheet metal having helical corrugations, and filling the shell with concrete in bearing contact with the lower section.

7. Method of setting composite piles, comprising arranging around the head end of a lower pile section of wood a sheet metal sleeve providing an annular space between the sleeve and said pile section, filling the annular space with concrete to reinforce the sleeve against deformation by pressures or stresses encountered in the ground, driving the wood section, arranging a pile shell above the wood section and locking the shell to the collar thereon, driving the wood section and shell into the ground, and filling the shell with concrete.

8. Method of setting composite piles comprising casting on a lower wood section at the upper end thereof a collar of reinforced concrete having external helical corrugations, screwing on the collar a helically corrugated sheet metal connecting sleeve, driving the lower wood section, screwing on the connecting sleeve an upper pile shell of helically corrugated sheet metal, driving the wood pile farther to carry the pile shell into the ground, and filling the shell with concrete in bearing contact with the lower section.

9. Method of setting composite piles comprising casting on a lower wood section at the upper end thereof a collar of reinforced concrete having external helical corrugations, screwing on the collar a helically corrugated sheet metal connecting sleeve, bending the connecting sleeve laterally to set the upper end thereof in vertical position, driving the lower wood section, screwing on the connecting sleeve an upper pile shell of helically corrugated sheet metal, driving the wood pile farther to carry the pile shell into the ground, and filling the shell with concrete in bearing contact with the lower section.

In testimony whereof I hereto affix my signature.

ELIHU D. WATT.
